UNITED STATES PATENT OFFICE.

WILLIAM MORTEN APPLETON, OF WESTON-SUPER-MARE, ENGLAND.

INTERNAL-COMBUSTION ENGINE.

1,004,720.

Specification of Letters Patent.

Patented Oct. 3, 1911.

Application filed April 15, 1911. Serial No. 621,264.

To all whom it may concern:

Be it known that I, WILLIAM MORTEN APPLETON, a subject of the King of Great Britain and Ireland, residing at Tyn-y-
5 Coed, Hill Road, Weston-super-Mare, in the county of Somerset, England, have invented certain new and useful Improvements in Internal-Combustion Engines, of which the following is a specification, reference being
10 had therein to the accompanying drawing.

This invention relates to internal combustion engines of the two-cycle type in which a pump or displacer is employed and arranged tandem fashion with respect to the power cylinder, and it has for its object increasing the efficiency of this type of engine, simplifying the construction and thereby reducing the cost of production. I attain this end by employing in each engine three
15 pairs of cylinders or multiples thereof, one of each pair being a displacer cylinder and the other a power cylinder, said cylinders being of different diameters and arranged tandem fashion and by an arrangement of
20 inlet, exhaust, and interconnecting ports hereinafter particularly specified whereby the pistons of the power cylinders only operate exclusively as distributing valves.

In the accompanying drawings which
30 illustrate—by way of example—an engine constructed according to this invention in which the scavenging of the power cylinders is effected by air which is taken into the displacer cylinder after the gaseous mixture
35 and is discharged therefrom in advance of said mixture, and in which the crank-shaft rotates clockwise:—Figure 1 is a view in side elevation, partly in section, Fig. 2 is a view in side elevation partly in section
40 through one of the cylinders, Fig. 3 is a diagrammatic view showing the three passages connecting the various ports of the three cylinders, Fig. 4 is a view in sectional plan on line A, A Fig. 2, Figs. 5, 6 and 7 are diagrammatic views illustrating the cycle of operations.

Throughout the views similar parts are marked with like letters of reference.

The three compound cylinders *a* and *a'*,
50 *b* and *b'* and *c* and *c'* are arranged side by side in close proximity to one another and the compound pistons *a*² and *a'*², and *b*² and *b'*² and *c*² and *c'*² are coupled by suitable connecting rods *d* to the crank-pins *d'*, *d''* and
55 *d'''* of a three-throw crank-shaft *d'*, said cranks being set at an angle of 120° to one

another. The smaller cylinders *a*, *b* and *c* are the power cylinders and the larger ones *a'*, *b'* and *c'* the displacer cylinders. It is immaterial in what relation to one another with respect to the crank-shaft the two cylinders of each pair are arranged, but the preferred construction is that shown in which the power cylinders are located above the displacer cylinder.

In each of the power cylinders *a*, *b* and *c* is an admission or inlet port *e*, an exhaust port *f*, an air port *g*, and two by-ports *h* and *k*, one of which *h*—hereinafter called the gas by-port—is for the passage of the gaseous mixture from the inlet port *e* of one cylinder to the displacer cylinder of one of the other pairs of cylinders, and the other by-port *k*—hereinafter called the by-pass port—is for the passage of the scavenging air and the gaseous mixture from the displacer cylinder of one of the other pairs of cylinders to the power cylinder. In each of the displacer cylinders *a'*, *b'* and *c'* is a port *l*—hereinafter called the distribution port. The admission or inlet ports *e* for the three power cylinders can conveniently open into a common chamber *m* which is coupled in any suitable manner to the carburetor or other device employed to produce the gaseous mixture. The exhaust ports *f* of the three power cylinders may be coupled or inter-connected in any suitable manner.

The gas by-port *h* in each power cylinder is so located with respect to the admission or inlet port *e* that it is put into communication with said port by a passage *n*—hereinafter called the gas admission passage—in the piston of said cylinder, when said piston has reached a predetermined position in its outward stroke which is approximately when the crank has moved through an angle of about 125°. The air port *g* which is open to the atmosphere is put into communication with the by-pass port *k* by a recess *p* in the power piston—hereinafter called the air inlet passage—when said piston has reached a certain position in its inward or return stroke, which is approximately when the crank has moved through an angle of about 220° on said stroke.

The distribution port *l* in each displacer cylinder is always open to said cylinder and is not controlled by the piston of said cylinder.

The gas by-port *h* of the power cylinder

of one pair, the by-pass port k of the power cylinder of another pair, and the distribution port l of the displacer cylinder of the third pair are all coupled together by a common passage—hereinafter called the distribution passage—and said passages r^1 , r^2 and r^3 , coupling the said respective ports of the three pairs of cylinders, are preferably contained within a single casing r adapted to be fixed over the ports of all the cylinders.

The cycle of operations can best be followed by reference to Figs. 5, 6 and 7 which show diagrammatically the positions of the various parts of the three pairs of cylinders during nearly a complete cycle of the cylinders a a^1 . In these views only one set of connections is shown between the by-pass port k and the distribution port l , and between the gas by-port h and the distribution port l in the center cylinder the port l is duplicated for the sake of distinctness. In Fig. 5 the compound piston a^2 a^3 of the cylinders a a^1 is on its inward or compression stroke. The by-pass port k of the power cylinder a has just closed, the exhaust port f of said cylinder is nearly closed, and the inlet port e has just been put out of communication with the gas by-port h , thereby cutting off the supply of gaseous mixture to the displacer cylinder c^1 . The compound piston b^2 b^3 of the compound cylinders b b^1 is at the top of its stroke and the charge in the power cylinder b is about to be fired. The air inlet passage p in the power piston b^2 has put the by-pass port k into communication with the air port g , thus allowing air alone to be sucked into the displacer cylinder c^1 . The compound piston c^2 c^3 of the compound cylinders c c^1 is on its outward stroke, the exhaust port f being partly uncovered and the inlet port e about to be put into communication with the gas by-port h by the gas admission passage n to allow a charge of gaseous mixture to pass into the displacer cylinder b^1 through the distribution port l .

In Fig. 6 the compound piston a^2 a^3 of the cylinders a a^1 is at the end of its inward or compression stroke and the air inlet passage p in the power piston a^2 has put the by-pass port k into communication with the air port g , thus allowing air alone to be sucked into the displacer cylinder b^1 . The compound piston b^2 b^3 is on its outward stroke, the power piston b^2 having commenced to open the exhaust port f , and the gas admission passage n in said piston being about to put the inlet port e into communication with the gas by-port h to put the displacer cylinder a^1 through the distribution port l into communication with the gas supply. The compound piston c^2 c^3 of the cylinders c c^1 has just started on its inward or compression stroke. The power piston c^2 has nearly closed the exhaust port

f , and the gas admission passage n in said piston has just cut off communication between the inlet port e and the gas by-port h , thereby cutting off the supply of gaseous mixture to the displacer cylinder b^1 .

In Fig. 7 the compound piston a^2 a^3 of the cylinders a a^1 is at the end of its outward stroke, both the exhaust port f and the gas by-port h are fully open, the latter admitting the air and the gaseous mixture from the displacer cylinder b^1 through the distribution port l to the power cylinder a . The inlet port e is in full communication with the by-pass port k through the gas admission passage n , thus allowing the displacer cylinder c^1 to take its charge of gaseous mixture through its port l . The compound piston b^2 b^3 of the cylinders b b^1 is approaching the end of its inward or compression stroke and the displacer cylinder b^1 is discharging its contents into the power cylinder a through the gas by-port h . The compound piston c^2 c^3 of the cylinders c c^1 is on its outward stroke, the piston c^3 of the displacer cylinder c^1 is drawing in a charge of gaseous mixture through the distribution port l in said cylinder and through the by-pass port h , the gas admission passage n and the inlet port e in the cylinder a .

It will be understood that in action the displacer cylinder of each pair of the three cylinders draws its gaseous mixture through the piston of the power cylinder of one of the other pair, its air—when air scavenging is employed—through the piston of the power cylinder of the third pair, and delivers both the air and the gaseous mixture, or the gaseous mixture alone, as the case may be, into the power cylinder of the third pair.

In an engine designed to have its working cylinders scavenged by the incoming charge of gaseous mixture and not by air, the power cylinders will not be provided with the air ports g , neither will the power pistons have the air inlet passages p , but the inlet ports e and the gas by-ports h will be arranged so that the displacer cylinders will be able to draw in a full charge of gaseous mixture through said ports.

It will be obvious that the power and displacer cylinders of each pair may be disposed in other positions relative to one another than that hereinbefore described and illustrated in the accompanying drawing without departing from the spirit and scope of this invention.

What I claim as my invention, and desire to secure by Letters Patent is—

1. In an internal combustion engine of the two-cycle type, the combination of three pairs of cylinders one of each pair being a power cylinder and the other a displacer cylinder, compound pistons working in said cylinders, an inlet port in each power cylinder, a gas by-port in each power cylinder, a

passage in each power piston adapted to put the inlet and gas by-port into communication during a predetermined part of the stroke of said piston, a by-pass port in each power cylinder for admitting the gas from the displacer cylinder, an exhaust port in each power cylinder, a distribution port in each displacer cylinder, and distribution passages each connecting the gas by-port 10 of the power cylinder of one pair, the by-pass port of the power cylinder of another pair, and the distribution port of the displacer cylinders, the arrangement of said ports and passages being such that in action 15 the displacer cylinder of each pair draws its gas through the piston of the power cylinder of one of the other pairs and delivers it into the power cylinder of the third pair.

2. In an internal combustion engine of 20 the two-cycle type, the combination of three pairs of cylinders—each pair being arranged tandem fashion and one of each pair being a power cylinder and the other a displacer cylinder—compound pistons 25 working in each pair of cylinders, an inlet port in each power cylinder, a gas by-port in each power cylinder, a passage in each power piston adapted to put the inlet and gas by-ports into communication during a 30 predetermined part of the stroke of said piston, a by-pass port in each power cylinder for admitting the gas from the displacer cylinder, an exhaust port in each power cylinder, a distribution port in each 35 displacer cylinder, and three distribution passages each connecting the gas by-port of the power cylinder of one pair, the by-pass port of the power cylinder of another pair, and the distribution port of the displacer cylinders, said passages being formed 40 in a single casting.

3. In an internal combustion engine of 45 the two-cycle type, the combination of three pairs of cylinders one of each pair being a power cylinder and the other a displacer cylinder, compound pistons working in said cylinders, an inlet port in each power cylinder, a gas by-port in each power cylinder, a passage in each power piston adapted to 50 put the inlet and gas by-ports into communication during a predetermined part of the stroke of said piston, a by-pass port in each

power cylinder for admitting the air and gas from the displacer cylinder, an exhaust port in each power cylinder, an air port in each power cylinder, a passage in each power piston adapted at a predetermined part of the stroke of said piston to put said air port into communication with the by-pass port, a distribution port in each displacer cylinder, and distribution passages 60 each connecting the gas by-port of the power cylinder of one pair, the by-pass port of the power cylinder of another pair, and the distribution port of the displacer 65 cylinders, the arrangement of said ports and passages being such that in action the displacer cylinder of each pair draws its gas through the piston of the power cylinder of the second pair, its air through the piston 70 of the power cylinder of the third pair, and delivers both the air and the gas into the power cylinder of the third pair.

4. In an internal combustion engine of the two-cycle type, the combination of a 75 series of compound single-acting cylinders, one of each pair being the power part and the other the displacer part, compound pistons working in said cylinders, an inlet port in each power part, a gas by-port in each 80 power part, a passage in each power piston adapted to put the inlet and gas by-ports into communication during a predetermined part of the stroke of said piston, a by-pass port in each power part, an exhaust 85 port in each power part, an air port in each power part, a passage in each power piston adapted at a predetermined part of the stroke of said piston to put said air port into communication with the by-pass port, 90 a distribution port in each displacer part, a distribution passage connecting the gas by-port of the power part of one cylinder, the by-pass port of the power part of another cylinder, and the distribution port of 95 the displacer part, all combined, arranged, and adapted to operate as set forth.

In testimony whereof I have hereunto signed my name in the presence of two subscribing witnesses.

WILLIAM MORTEN APPLETON.
